LIQUID DISPENSING ROLLER

Earle M. King, Salinas, Calif., assignor to Gabilan Iron and Machine Co., Salinas, Calif., a corporation of California

Application February 8, 1947, Serial No. 727,429

10 Claims. (Cl. 222—167)

1

This invention is directed to, and it is an object to provide, an implement supporting roller formed as a liquid reservoir and arranged with novel means to deliver liquid from the roller to another point on the implement. As an example, the invention may be used on an automatic planting machine to supply water to the plants deposited in the ground.

Another object of the invention is to provide a liquid dispensing roller, as above, which serves not only to supply liquid for use on the implement, but also supports one end of the same and acts as a very effective clod breaking and soil packing instrumentality.

A further object of the invention is to embody, in assembly with the roller, a novel liquid elevating arrangement operative, upon advance of said roller, to elevate water from below the roller axis and to deliver said water for discharge from one end of the roller at said axis.

A further object of the invention is to produce a practical liquid dispensing roller, and one which will be exceedingly effective for the purpose for which it is designed.

These objects are accomplished by means of such structure and relative arrangement of parts as will fully appear by a perusal of the following specification and claims.

In the drawings:

Fig. 1 is an elevation of the roller, partly in section.

Fig. 2 is a cross section of the roller taken on line 2—2 of Fig. 1.

Fig. 3 is a fragmentary diagrammatic side elevation of an implement embodying the present invention.

Referring now more particularly to the characters of reference on the drawings, the roller is indicated generally at 1, and comprises a hollow drum having end walls 2 and 3; the end wall 3 being offset axially inwardly somewhat relative to the adjacent end of the roller.

The roller is formed with a tubular axle 4 which projects, at opposite ends, some distance beyond the end walls 2 and 3, and is there carried in journals 5 supported from the side beams 6 of the main implement frame, indicated generally at 7. In addition to its other functions, the roller provides the supporting means for one end of said main frame 7.

Outwardly of the roller end wall 3, and formed in part with the projecting end portion 8, the roller includes a plurality of elongated, circumferentially extending liquid pick-up chambers 9; said chambers being four in number in the pres-

2

ent embodiment, and equally spaced about the roller adjacent its periphery.

The roller turns in the direction indicated by the arrow in Fig. 2, and at their leading ends the chambers 9 communicate with the interior of the hollow roller 1 by means of ports 10 in the end wall 3.

At their trailing ends, and on the radially innermost side, the chambers 9 are formed with ports 11 which communicate with radially inwardly extending conduits 12; there being a ball check valve unit 13 in each conduit. The ball check valve units 13 open away from the ports 11 and function in the manner hereinafter described.

At the end opposite the ball check valve unit 13, and adjacent the port 10, each chamber 9 is fitted with another check valve unit 14 which closes in a direction away from said chamber, i. e. opens to permit air entry into the corresponding chamber at a predetermined time, as will be hereinafter described.

At their inner ends the conduits 12 connect with an annular, feed reservoir 15, formed in surrounding relation to the tubular axle 4 adjacent and outwardly of the end wall 3. The annular, feed reservoir 15 communicates with the tubular axle 4 through openings 16 in the latter.

A stationary fitting 17 projects through a packing gland 18 in the end portion of the tubular axle 4 adjacent the reservoir 15; liquid from said reservoir being adapted to deliver therefrom, through the openings 16 into the axle 4, and thence out through the stationary fitting 17. From the fitting 17 liquid delivers through an outlet conduit 19 which connects to a pipe system 20 having a valve 21 interposed therein.

At the end portion opposite the stationary fitting 17 the tubular axle 4 is provided with an end head or closure 22, and at said end the axle 4 is fitted with a stub shaft 23 adapted to drive an endless chain and sprocket unit, indicated in part at 24. The unit 24 can be employed to drive, in a positive manner and in timed relation to ground speed, a mechanism on the implement main frame 7, such as a planting wheel assembly (not shown).

Beyond the valve 21 in the pipe system 20 liquid is delivered from said system for its intended use, as for example to discharge into the furrow formed by a furrow opening shoe 25, as is incorporated in a planting machine; the planting mechanism working to deposit the plants in said furrow.

The roller will be described, by way of ex-

ample, as it is used to dispense water in an automatic planting machine.

At the outset a quantity of water is placed in the hollow roller 1 through a filler opening of any convenient type. While the water line in the roller is above its axis, the water feeds by gravity through the ports 10, chambers 9, and conduits 12, into the feed reservoir 15, and thence into the tubular axle 4 and out of the roller in the manner previously described.

However, when the water line in the roller falls below the axis thereof, as for example at 26 in Fig. 2, the dispensing mechanism functions as follows:

As each reservoir reaches station A, it is filled with water from the roller through the port 10, the check valve units 13 and 14 then being closed. As each chamber 9 reaches station B and begins to travel towards station C at the top of the roller, the corresponding check valve unit 13 opens, permitting the water from such chamber to deliver through the corresponding conduit 12 into the feed reservoir 15; each chamber 9 being fully empty by the time it reaches the top station C. As the water delivers from each chamber 9 through the conduit 12 air enters, by suction, through the corresponding check valve unit 14 to replace the fluid volume in the roller assembly.

Between stations C and D each chamber 9 remains empty, the corresponding check valve unit 13 being closed by the water pressure from feed reservoir 15 exerted through the corresponding conduit 12 as said chamber reaches station D; both check valve units 13 and 14 being closed by the time the chamber 9 passes below the water line 26 for refilling through the corresponding port 10. By the time each chamber reaches the bottom of the roller, it is filled with water ready for another rotation with the roller and discharge into the feed reservoir 15 in the manner described.

It is thus evident that a quantity of water is recurringly fed into the reservoir 15 for delivery to the pipe system 20, even though the water line 26 in said roller may be below the axis of the latter.

Depending on the type of implement in which the invention is embodied, the valve 21 may be hand actuated, or automatically actuated, from and in timed relation to, rotation of the roller 1. In an automatic planting machine, for example, the valve 21 would be automatically opened from the roller 1 in timed relation to deposit plants in the furrow opened by the shoe 25; the planting mechanism likewise being driven by, and timed from, said roller through the medium of the endless chain and sprocket unit 24.

Although the invention is herein mentioned as used in connection with an automatic planting machine, it is evident that it has many other adaptations, such as the dispensing of liquid fertilizer or the like.

A further advantage of the invention which should be noted is the fact that the roller, serving as a liquid supply tank, avoids the necessity of such a tank, with reinforcing structure, on the main frame 7.

From the foregoing description it will be readily seen that there has been produced such a device as substantially fulfills the objects of the invention, as set forth herein.

While this specification sets forth in detail the present and preferred construction of the device, still in practice such deviations from such

detail may be resorted to as do not form a departure from the spirit of the invention, as defined by the appended claims.

Having thus described the invention, the following is claimed as new and useful, and upon which Letters Patent are desired:

1. A liquid dispensing roller structure for an implement which includes a frame, comprising a hollow roller adapted to receive a quantity of liquid therein, means adapted to mount the roller in supporting relation to the frame, a conduit having a fitting mounted in connection with the roller centrally at one end thereof, and means arranged with the roller operative upon rotation thereof to elevate liquid from within the roller below the roller axis and deliver said liquid into the fitting; said means including a plurality of circumferentially extending and spaced chambers formed on said end of the roller adjacent the periphery of the roller, said chambers being in communication at their leading ends with the interior of the roller, conduits connected with said chambers adjacent their trailing ends and extending toward the axis of the roller, and a reservoir formed centrally on the roller at said end and to which reservoir the last named conduits connect, the fitting being in communication with such reservoir.

2. A liquid dispensing roller structure for an implement which includes a frame, comprising a hollow roller adapted to receive a quantity of liquid therein, means adapted to mount the roller in supporting relation to the frame, a conduit having a fitting mounted in connection with the roller centrally at one end thereof, and means arranged with the roller operative upon rotation thereof to elevate liquid from within the roller below the roller axis and deliver said liquid into the fitting; said means including a plurality of circumferentially extending and spaced chambers formed on said end of the roller adjacent the periphery of the roller, said chambers being in communication at their leading ends with the interior of the roller, conduits connected with said chambers adjacent their trailing ends and extending toward the axis of the roller, and a reservoir formed centrally on the roller at said end and to which reservoir the last named conduits connect, the roller mounting means including a tubular shaft into which the reservoir feeds and the fitting being in communication with said shaft at the adjacent end.

3. A liquid dispensing roller structure for an implement which includes a frame, comprising a hollow roller adapted to receive a quantity of liquid therein, means adapted to mount the roller in supporting relation to the frame, a plurality of circumferentially extending and spaced chambers formed on one end of the roller adjacent the periphery of the roller, said chambers being in communication at their leading ends with the interior of the roller, conduits extending radially inward from the trailing ends of the chambers, a central reservoir formed on said one end of the roller, the conduits connecting to said reservoir, and an outlet fitting leading from said reservoir axially of the roller, there being a check valve unit in each conduit opening toward the reservoir but operative to close when the corresponding chamber is below the roller axis.

4. A liquid dispensing roller structure for an implement which includes a frame, comprising a hollow roller adapted to receive a quantity of liquid therein, means adapted to mount the roller in supporting relation to the frame, a plu-

rality of circumferentially extending and spaced chambers formed on one end of the roller adjacent the periphery of the roller, said chambers being in communication at their leading ends with the interior of the roller, conduits extending radially inward from the trailing ends of the chambers, a central reservoir formed on said one end of the roller, the conduits connecting to said reservoir, and an outlet fitting leading from said reservoir axially of the roller; there being a check valve unit in each conduit opening toward the reservoir but operative to close when the corresponding chamber is below the roller axis, and other check valve units on the chambers operative to admit air thereinto when the chambers are above said axis.

5. A liquid dispensing roller structure for an implement which includes a frame, comprising a hollow shaft journaled for rotation relative to the frame, a hollow roller fixed to the hollow shaft, a reservoir on the outside of one end wall of the drum and surrounding the shaft, means establishing communication between the reservoir and the interior of the shaft, a plurality of chambers formed on the outside of said one end of the drum in circumferentially spaced relation adjacent the outer periphery of the drum, each chamber having a leading end and a trailing end with respect to the direction of rotation of the drum, the end of the drum being provided with port each establishing communication between the interior of the drum and one of the chambers adjacent the leading end of the chamber, and a conduit interposed between the trailing end of each chamber and the reservoir.

6. A structure as in claim 5 including a check valve in each conduit, such valves opening in a direction away from the chambers.

7. A structure as in claim 6 including a check valve in an outside wall of each chamber adjacent the trailing end thereof and closing in a direction away from the chamber, such last named valves being effective to open communication between the atmosphere outside the drum and the interior of the chambers in one position of the drum.

8. A liquid dispensing roller structure for an implement which includes a frame, such structure comprising a hollow roller adapted to receive and carry a quantity of liquid therein, a tubular shaft extending through the roller concentric therewith and fixed thereto, the ends of the shaft projecting beyond the ends of the roller, means journaling the projecting ends of the shaft on the frame for rotation relative to

the frame, a fitting fixed to the frame and disposed in communication with the interior of the shaft at one end thereof, a conduit leading from the fitting to a point of discharge, and conduit means interposed between the interior of the drum and the interior of the shaft and operative to convey liquid from the drum at a point below the drum axis and discharge such liquid into the shaft.

10. A liquid dispensing roller structure for an implement which includes a frame, comprising a hollow roller adapted to receive a quantity of liquid therein, means adapted to mount the roller in supporting relation to the frame, a plurality of circumferentially extending and spaced chambers formed on one end of the roller adjacent the periphery of the roller, said chambers being in communication at their leading ends with the interior of the roller, a central enclosed reservoir fixed on said one end of the roller and rotatable therewith; direct, enclosed, fixed communicating conduits between the trailing end of each chamber and the reservoir, and an outlet fitting leading from said reservoir axially of the roller.

15. A liquid dispensing roller structure for an implement which includes a frame, comprising a hollow roller adapted to receive a quantity of liquid therein, means adapted to mount the roller in supporting relation to the frame, a plurality of circumferentially extending and spaced chambers formed on one end of the roller adjacent the periphery of the roller, said chambers being in communication at their leading ends with the interior of the roller, a central enclosed reservoir fixed on said one end of the roller and rotatable therewith; direct, enclosed, fixed communicating conduits between the trailing end of each chamber and the reservoir, and an outlet fitting leading from said reservoir axially of the roller; said mounting means including a tubular shaft on the roller, the reservoir being in communication with the interior of the shaft, and said outlet fitting being on one end of such shaft.
